(57) **CLAIM**

The ornamental design for a breastfeeding sling for supporting a breast as shown and described.

DESCRIPTION

FIG. 1 is a front view of a breastfeeding sling for supporting a breast showing my new design, wherein a cupped portion of the design has been spread to accommodate a breast.

FIG. 2 is a top view of the breastfeeding sling for supporting a breast;

FIG. 3 is a bottom view thereof; and,

FIG. 4 is an alternate position view thereof, wherein a bottom side of a strap portion of the design is visible.
